UNITED STATES PATENT OFFICE.

THOMAS P. KING, OF CHESTER, ILLINOIS.

MACHINE FOR PRICKING BOOT AND SHOE HEELS.

SPECIFICATION forming part of Letters Patent No. 315,636, dated April 14, 1885.

Application filed July 25, 1884. (No model.)

To all whom it may concern:

Be it known that I, THOMAS P. KING, a citizen of the United States, and a resident of Chester, in the county of Randolph and State 5 of Illinois, have invented certain new and useful Machines for Pricking Boot and Shoe Heels, of which the following is a specification.

My invention relates to a machine for prick- 10 ing holes in boot and shoe heels in order to prepare them to receive the nails or pegs by which the layers of leather are held together and the heel secured to the boot or shoe.

The invention consists in certain novel de- 15 tails of construction, arrangement, and combination of the various parts of the machine, whereby provision is made for adapting it to heels of various heights and thicknesses, and for changing the direction of the holes in order 20 to accommodate it to heels of different shapes.

The accompanying drawings illustrate a mode of carrying out my invention.

Figure 1 is a side view, partly in section, of a machine embodying my improvements. Fig. 25 is a front view of the same, also partly in section. Fig. 3 is an end view, and Fig. 4 a detail top view.

The main driving-shaft of the machine is carried by a vertical pedestal, A, secured to 30 the floor, and having at its upper end a horizontal arm, A², extending toward the front of the machine. The shaft B has one bearing in the upper end of the pedestal, and the other bearing in a plate, C, carried by the front end 35 of the arm A².

At the rear end of the shaft B is a belt-pulley, D, to which is attached a wheel or disk, D², considerably larger than the pulley. On the rear side of this disk is a rim or circular 40 rib, d, and near the center is a similar rib, d², thus forming an annular groove, d³, on the rear side of the disk. The rear end of the shaft B passes through the center of the pulley and disk and extends beyond the rear side 45 of the disk. To this projecting portion of the shaft is attached a spring or elastic arm, E, by means of a hub, e, on one end fitting on the shaft B, and a set-screw, f, passing through said hub and bearing against the shaft. In 50 the face of the inner rib, d², is a notch, g, one side of which is abrupt and the other side is inclined. The free end of the spring or elas-

tic arm E engages with this notch, so that when the pulley D and disk D² are revolved in the direction of the arrow in Fig. 3 the 55 shaft B is made to revolve in the same direction. In the pedestal A a bent lever, G, has its fulcrum. The long arm 1 of this lever extends outward within reach of the operator of the machine, and the short arm 2 extends 60 upward and works in the annular groove d³ in the rear side of the disk D², the end of said short arm being tapering or wedge-shaped. When the long arm 1 of the lever G is depressed, the short arm 2 works near the outer 65 rim or rib, d, and does not interfere with the spring or elastic arm E. When the long arm 70 1 of the lever is raised, the short arm 2 is thrown toward the center and against the inner rib, d², so as to pass under the end of the 75 spring or arm E and lift it out of the notch g. The two positions of the lever are shown in Fig. 3 in full lines and dotted lines, respectively. The arm being thus released from the notch, the disk and pulley, being loose on the 80 shaft, continue to revolve; but the revolution of the shaft itself is stopped.

On the front end of the shaft B is a cam or eccentric, H, which works in a seat formed in the face of the plate C. In front of this plate 85 C is another plate, K, of similar shape and size, and provided with a seat for the reception of the cam or eccentric H. The plate K is connected to the plate C by a tongue-and-groove connection, so that the plate K may reciprocate horizontally. The seat in the plate C is large enough to allow free motion to the cam when it is revolving with the shaft B. The seat in the plate K is of smaller dimensions than the circle described by the periphery of the cam in its revolution, so that as the cam H revolves it causes the plate K to reciprocate horizontally in front of the plate C. To the edge of the plate K is attached one end 90 of a short bar, J, the other end of which is provided with a hole, through which a screw, i, passes loosely and engages with a thread at the bottom of a hole, c, in the edge of the plate C. The hole c forms a seat for a spring, L, which surrounds the screw i and presses 95 against the bar J, and thus co-operates with the cam in giving the reciprocating motion to the plate K.

The awl-carrier consists of a bar, M, sliding

vertically in ways provided in the plate K. It is provided with a seat consisting of a recess between two shoulders or abutments, m m, (shown in dotted lines in Fig. 1,) the distance between which shoulders or abutments is less than the circle described by the periphery of the cam in its revolution, so that as the cam revolves the awl-carrier is alternately raised and lowered by the engagement of the cam between the shoulders. Thus, by the operation of the cam in connection with the awl-carrier and the plate in which it works, at each revolution of the cam the awl is made to descend to prick a hole in the heel, and as the awl rises it is carried laterally to bring it to the proper point to make the next hole.

At the bottom of the plate C is a plate, N, provided with a horizontal lip, n, and a downwardly-projecting lip, n². The lip n serves as a gage for the top of the heel, and the lip n² serves the same purpose for the edge of the heel when being operated upon, as shown in Fig. 1, where the heel h is shown in dotted lines.

25 In front of the pedestal A, and immediately under the awl-carrier, is a vertical pedestal, P, which is hollow, and is lined with a sleeve, P², in which is a vertical groove or slot, p. In this sleeve rests a spiral spring, S. Fitting 30 within this spring is a stem, Q, having on one side a projecting pin or stud, q, engaging with the groove or slot p. The length of the stem Q is less than the depth of the sleeve or tube P². The spring S has its lower end resting at the 35 bottom of the sleeve or tube, and its upper end bears against a shoulder on the stem. The spring prevents the stem from descending too low, and the pin q and slot p prevent it from turning in its seat. The upper end of the 40 stem Q carries a circular flat-surfaced plate or disk Q². The stem Q is hollow, and in the center of the plate Q² is a hole corresponding with the hollow stem. Through this hole and into the hollow stem passes another stem, R, 45 on one side of which is a vertical groove, r, with which engages a pin or stud, s, on the inner surface of the hollow stem Q, to prevent the stem R from turning. At the upper end of the stem R is a block or follower, R², sur- 50 mounted by a plate, R³, which projects on two opposite sides beyond the block or follower, and has its projecting portions provided with screw-threaded holes, in which work screws T T. Projecting from the center of the plate 55 R³ is a post or stem, t, to which is pivoted by means of lugs v, a plate or disk, V, for holding the heel h to be operated upon. On the upper side of the plate or disk Q² is a cam, W, composed of an inclined plane running spirally. It is pivoted toward one side of the center of the plate, and is provided with a handle, w, for operating it. The length of the cam is somewhat greater than a half-circle drawn from its pivot w² as a center, and it is 60 provided with a slot forming an arc drawn from said center, through which are the stem

R passes, so that the block or follower R² rests upon the circular inclined plane of the cam.

The machine constructed and arranged as above described is operated as follows: The 70 heel h is held by the operator on the top of the plate V, and is gaged by the lips n n². The spring S allows the work to yield sufficiently to prevent too much jar, and the pins and grooves before described prevent the 75 stems from turning in their seats as the work is turned by the operator. At each descent of the awl a hole is pricked in the heel, and at each ascent the awl is moved laterally to prepare for pricking the next hole, as 80 before described. If the heel is to be a low heel, the plate or heel-carrier V is raised to the proper height by moving the cam W toward the left-hand side of Fig. 1. If it is to be a high heel, the carrier V is lowered by 85 turning the cam in the opposite direction. If the nails are to be driven vertically, the carrier is placed in a horizontal position. If they are to be driven slantingly, either inward or outward, the carrier V is inclined at the de- 90 sired angle by means of the screws T by screwing them in opposite directions. By this means provision is made for driving the nails in any desired direction, in order to provide for straight heels or for those which are either 95 larger or smaller at the top than at the base.

What I claim as new, and desire to secure by Letters Patent, is—

1. In a machine for pricking holes in boot and shoe heels, the heel-carrier V, suitably supported upon a pedestal, combined with the cam W, supported by a table or plate intermediate of the pedestal and heel-carrier, whereby the said heel-carrier may be elevated or depressed independently of the adjustment of 100 the vertically-movable parts of said pedestal, in order to accommodate the machine to high or low heels, substantially as herein set forth.

2. In a machine for pricking holes in boot and shoe heels, the heel-carrier V, supported 110 upon a vertically-yielding stem within a pedestal, and pivoted centrally, as described, combined with devices—such as T—for inclining said heel-carrier toward or from a horizontal position, whereby the machine may be adjusted 115 to heels in which the nails are to be driven either vertically or slantingly inward or outward, substantially as herein set forth.

3. In a machine for pricking holes in boot and shoe heels, the hollow pedestal P and 120 sleeve P², combined with the externally-shoudered stem Q, provided with the plate Q², and spring S, whereby the work is permitted to yield under the stroke of the awl, substantially as herein set forth.

4. In a heel-pricking machine, the hollow stem Q, provided with the plate Q², in combination with the cam W and stem R, provided with the follower R², whereby the heel-carrier is raised or lowered, substantially as herein set forth. 130

5. In a heel-pricking machine, the sleeve

P², having the vertical groove or slot p, and the hollow stem Q, having the external pin, q, and the internal pin, s, in combination with the stem R, having the vertical groove r, whereby the work may be raised or lowered, but is prevented from turning on its carrier, substantially as herein set forth.

5 6. In a heel-pricking machine, the plate R³, suitably supported as described, in combination with the pivoted heel-carrier V and the screws T T, whereby the heel-carrier may be oscillated and inclined at different angles, substantially as herein set forth.

10 7. In a heel-pricking machine, the adjustable heel-carrier V, substantially as described, in combination with the awl-head provided with the gage N, having the lips n n² at right angles to each other, whereby the work is prop-

erly guided for the action of the awl, substantially as set forth.

20 8. In a heel-pricking machine, the stationary plate C, movable plate K, and cam H, in combination with the awl-carrier M, having a seat formed by the shoulders m m, whereby the plate K has imparted to it a slight laterally reciprocating motion, and the awl a vertically-reciprocating motion, substantially as and for the purposes herein set forth.

25 Signed at Chester, in the county of Randolph and State of Illinois, this 15th day of July, A. D. 1884.
